UNITED STATES PATENT OFFICE.

THOMAS H. WHETTON, OF HAMILTON, ONTARIO, CANADA.

WINDOW-BLIND.

1,268,413.

Specification of Letters Patent. Patented June 4, 1918.

Application filed July 24, 1917. Serial No. 182,453.

To all whom it may concern:

Be it known that I, THOMAS H. WHETTON, a subject of the King of Great Britain, residing at Hamilton, Province of Ontario, Dominion of Canada, have invented certain new and useful Improvements in Window-Blinds; and I do hereby declare the following to be a full, clear, and exact description of the invention, such as will enable others skilled in the art to which it appertains to make and use the same.

This invention relates to new and useful improvements in window blinds and the principal object of the invention is to provide a window blind patterned after the ordinary Venetian blind which is arranged to be readily folded in its raised position and which is provided with guides fixed to the window casing in such a manner as to control the opening and closing of the blind.

Another object of the invention is to provide a blind consisting of a plurality of pivotally mounted slats or laths which are arranged to be adjusted to various angles when the blind is in open or operative position so as to control the amount of light admitted to a room.

Still another object of the invention is to provide a novel form of guide and controlling mechanism for the blind which may be readily attached to an ordinary window casing.

With these and other objects in view, the invention consists in the novel combination and arrangement of parts which will be fully set forth in the following specification and accompanying drawings, in which:—

Figure 1 is a face view of the blind constructed in accordance with this invention.

Fig. 2 is a vertical sectional view on an enlarged scale taken on line 2—2 of Fig. 1 and showing the blind partly closed.

Fig. 3 is an enlarged fragmentary view showing the window casing and guide rods attached thereto and showing the blind partially lowered.

Fig. 4 is a view illustrating the position of the blind when in its raised position, and

Fig. 5 is a detail perspective view of part of the connecting links of the device.

Referring to the drawings, 1 designates a window casing of the ordinary construction provided with the usual vertical stiles 2 on which the guide rails of the blind are mounted. The guide rails above referred to are designated by the numeral 3 and supported

in suitable brackets 4 at the upper and lower ends of the stile as will be clearly seen upon reference to Fig. 1. Mounted adjacent the guide rails 3 and spaced inwardly toward the center of the window therefrom for a short distance are the guide bars 5 which are provided at their upper ends with the head 6 having the curved upper faces 7 the use of which will appear as the description proceeds. As shown in the drawings the upper ends of the guide rails 5 are positioned below the upper ends of the guide bars 3 and the rails are positioned in a plane inwardly from the plane of the guide bars as clearly shown in Fig. 3. The lower ends of the guide rails are supported in the brackets 8 arranged adjacent the brackets 4 at the lower ends of the guide bars as will be clearly seen upon reference to Fig. 1.

Slidably mounted on the guide bars 3 are suitable eyes 9 provided with the shanks 10 which project through the central portion of the links 11 and into the ends of the slats or laths 12. It will thus be seen that the laths are supported pivotally on the guide bars and may be adjusted to control the quantity of light admitted to or excluded from the room in which the device is used. The links 11 are arranged when the curtain is lowered to engage against the guide rails 5 as illustrated in Figs. 2 and 3 so that their lower ends contact with said rail while their upper ends are positioned against the next adjacent links immediately thereover. The lower ends of the links are connected by suitable connecting links 13 to the central portion of the link immediately beneath the same as clearly illustrated in Fig. 5 and these links 13 are pivoted as shown at 14 to the lower end of the upper link and the lower ends of the links 13 are provided with openings 15 for the reception of the shanks 10 of the eyes 9. It will thus be seen that a train like structure is provided having the upper ends of its alternate links extended to engage against the links immediately thereover when the blind is in its lowered position.

In order that the positions of the slats or laths 12 may be simultaneously adjusted suitable connecting cords 16 are attached to their opposite side edges and it will be seen that upon exerting pull on one or the other of the cords the laths will be swung on their pivot. A suitable elevating roller 17 is mounted on a bracket 18 projecting out-

wardly from the window casing as shown in Fig. 2 and this roller has wound thereon a flexible member 19 which is connected at its lower end to the bottom lath or slat 20 of the blind. A suitable controlling cord 20' is arranged to control the rotation of the roller 17 and a pulling cord 21 is connected to the bottom slat 22 by means of which the device is lowered.

10 It will be apparent from the foregoing that in use the blind is set up in the manner illustrated and when it is desired to lower the same pull is exerted on the cord 22 until the blind is in the proper position. Should 15 it be so desired it will be evident that the slats may be swung on their pivot to control the quantity of light admitted to the room and when it is desired to raise the same pull is exerted on the cord 21 and it will be evident that the cord 19 will wind upon the roller 17 thereby moving the lower end of the blind upwardly and causing the links to fold in the manner shown in Fig. 2 until the 20 slats are moved so their adjacent faces engage each other as will be clearly seen upon reference to the figure above mentioned and in this way it will be seen that the blind may be readily raised and lowered and will be held against blowing about by the wind due 25 to the fact that it is slidably mounted on the guide rods 3.

While in the foregoing there has been shown and described the preferred embodiment of this invention, it is to be understood 30 that such changes may be made in the combination and arrangement of parts as will fall within the spirit and scope of the appended claims.

What is claimed is:—

40 1. In a blind of the class described, a pair of guide bars attached to the stiles of a window, slats positioned between the guide bars, shanks extending longitudinally from the slats, and having eyes on the ends thereof 45 which surround the guide bars to prevent the blind from being blown about, links on the shanks to facilitate in the folding of the blind and means controlling the raising and lowering of the blind.

2. A blind comprising a pair of guide bars 50 attached to the stiles of a window casing, shanks having eyes formed on one end and surrounding said guide bars, slats pivotally mounted on the adjacent ends of the shanks, links pivotally mounted on the shanks, guide 55 rods attached to the stiles of the window casing immediately behind the links and forming bearings for the links, connecting links connecting the lower ends of the first mentioned links with the links immediately 60 beneath the same, means to move all of the slats simultaneously upon the movement of one of said slats and means controlling the raising and lowering of the blind.

3. In a blind of the class described, a pair 65 of guide rails secured to the stiles of a window, slats positioned between the guide rails, shanks extending longitudinally from the slats and having eyes formed on the ends thereof and slidably engaging the rails to 70 prevent the blind from being blown out, links pivoted to the shanks and slats, said links permitting the blind to fold when being raised, guide bars secured to the stiles of the window frame in rear of the guide rails, 75 said slats adapted to engage the guide bars during the folding and unfolding action thereof, and means controlling the raising and lowering of the blind.

4. A blind comprising a pair of guide 80 rails attached to the stiles of a window casing, shanks having eyes on one end which surround said guide rails, slats pivotally mounted on the adjacent ends of the shanks, links pivotally mounted on the shanks, guide 85 bars attached to the stiles of the window casing immediately behind the links and forming bearings for the links to facilitate the raising and lowering of the blind by engagement with the slats, and means for raising 90 and lowering the blind.

In testimony whereof I affix my signature in presence of two witnesses.

THOMAS H. WHEATTON.
